CONSTRUCTION FOR ELECTROLYTIC CELL
Joshua Szechtman, Byram, Conn., assignor to Chloro-
metals Incorporated, New York, N.Y., a corporation
of Delaware
Continuation of application Ser. No. 89,943, Feb. 17,
1961. This application May 26, 1964, Ser. No. 377,162
6 Claims. (Cl. 204—219)

This is a continuation of my co-pending application Serial No. 89,943, filed February 17, 1961 now abandoned.

This invention relates to an electrolytic cell of the type involving a mobile cathode which flows in relation to at least one fixed anode, and the invention is more particularly concerned with the control or adjustment of the "gap" between the cathode and the anode.

In the electrolysis of alkali metal salts and alkaline earth metal salts, use is made of electrolytic cells of the mobile cathode type which employ, as the cathode, a liquid metal which flows across the sole of the cell. Electrolytic cells of the mercury-cathode type are well known and, in U.S. Patent No. 3,104,213 of September 17, 1963, I have described a cell which is adapted to be operated with a molten electrolyte and which employs molten lead as the cathode. The mercury-cathode electrolytic cell is commonly employed for the electrolysis of aqueous salt solutions, particularly sodium chloride brine, and the liberated metal, e.g. sodium, combines with the mercury to form an amalgam. In the cell of my above-mentioned patent, the liberated metal combines with the molten lead to form an alloy from which the metal can be subsequently readily recovered, e.g. by distillation. The anodes of electrolysis cells of the liquid-cathode type are generally formed from graphite and are electrically connected to a source of electrical current. In the most satisfactory commercial cells of the horizontal type, each graphite anode is in the form of a block having a substantially planar lower surface which is disposed at a predetermined distance from the surface of the flowing cathode. This distance is referred to as the anode-cathode "gap," and the voltage in the cell varies, of course, with the size of the gap. During normal operation of the cell, each graphite anode is gradually worn away, and this wear is generally localized at the lower surface of the anode. Since the flow of the cathode remains substantially constant, wearing away of the lower surface of the anodes gradually increases the anode-cathode gap, and this increase in the size of the gap causes a gradual increase in the voltage. A certain amount of voltage increase can be tolerated but after it has reached a maximum practical value, which depends upon the particular cell, further increase in voltage must be prevented if economical operation of the cell is to be achieved. Accordingly, it has been customary to lower the anodes from time to time to reduce the anode-cathode gap to the optimum distance, e.g. the distance at which each anode was originally set when new. While such operation does, of course, compensate for the wear of the anodes and keeps the voltage within practicable operating limits, this method has certain practical disadvantages. The graphite anodes have a stem or support extending upwardly through the cover plate of the cell and to permit the lowering of the anodes to compensate for wear, as just described, it is necessary to provide for sliding movement of the anode stem in the cover plate. This makes necessary the provision of special means which will permit the sliding movement and yet which will retain the fluid-tightness of the cell. From a practical standpoint this presents many problems and is not wholly satisfactory. Various other proposals have been made

2

to solve the problem of compensating for anode wear, but all suffer from one or more practical disadvantages and generally involve a complicated and expensive construction.

5 It is an object of the present invention to provide an electrolytic cell which includes means for regulating and adjusting the anode-cathode gap which avoids the drawbacks and disadvantages enumerated above.

It is a further object of the invention to provide a 10 method for adjusting the anode-cathode gap of a horizontal electrolytic cell of the liquid cathode type without requiring any shifting of the anodes.

In accordance with the invention, the anode-cathode gap of a liquid-cathode electrolytic cell is adjusted and 15 maintained at the optimum value by controlled regulation of the level of the flowing cathode stream in the cell. More particularly, there is provided, in accordance with the invention, a cell construction having an outlet for the liquid-cathode stream associated with means 20 for selectively positioning the level at which the cathode flows into the outlet and, therefore, the level of the cathode stream flowing under the anodes in the electrolysis chamber. More specifically, there is provided, in accordance with the invention, an electrolytic cell of 25 the liquid-cathode type in which the outlet is defined by a sleeve member which is combined with vertical adjustment means for selectively raising and lowering the sleeve in relation to the bottom of the cell.

It is a feature of the invention that the anode-cathode 30 gap in an electrolytic cell of the liquid-cathode type can be continuously maintained at any desired value without the necessity for moving the anodes in any way.

It is a further feature of the invention that maintenance of the anode-cathode gap at an optimum value can 35 be achieved without interrupting cell operation.

It is another feature of the invention that the control system provided by this invention for adjustment of the anode-cathode gap lends itself readily to completely automatic operation.

40 Other objects and features of the invention will be readily apparent from the following detailed description of an illustrative embodiment thereof and from the accompanying drawings wherein:

FIG. 1 is a longitudinal cross-sectional view of an electrolytic cell embodying features of the present invention; and

FIG. 2 is an enlarged view of the right-hand portion of FIG. 1 showing the details of the construction of the cathode-level adjusting mechanism.

50 Referring to the drawings, there is illustrated an electrolytic cell designated generally by the reference numeral 10. The cell body 12 of the cell 10 is suitably formed from metal, and is supported upon an insulating support 14 indicated in the drawing as refractory blocks or bricks, but it will be understood that any other convenient insulating base may be employed. As seen in FIG. 1, the cell 10 defines a sole surface 15 upon which the liquid cathode 16, e.g. molten lead, is adapted to rest and to flow from left to right. Thus, the elongated cell body 12 is formed with an elongated channel of which the sole 15 is the bottom and which provides the electrolysis chamber 17. The sole 15 may be horizontal or it may slope slightly toward the right, the slope of the cell may vary but a slope of 1° or less is preferred. When the cell is adapted to be operated at elevated temperatures for the electrolysis of molten salts, e.g. temperatures of 810° to 850° C. which are suitable for the electrolysis of molten sodium chloride, any convenient means for heating the cell body and maintaining it at an elevated temperature may be employed. Actually, the electrolysis reaction is exothermic but the heating means is 55 60 65 70

provided in order to bring the cell to operating temperature and to minimize heat loss so that desired operating temperature is always maintained.

Closing the cell is a cover 30 which extends completely across the cell body 12 and also extends from one end of the cell body to the other. This cover is formed from an electrically-conductive material and, most suitably, it is formed from graphite.

The cover 30 directly supports the anodes 50 and such support is effected by means of anode stems 52. While in U.S. Patent No. 3,104,213 I show a conduit extending through the cover for the removal of chlorine generated in the cell during electrolysis, and a similar outlet is shown at 55 in FIG. 1, provision may be made for withdrawing chlorine from the cell through the anodes and through the cover in the manner described in French Patent No. 1,287,758.

The power connections are indicated diagrammatically at 56 and 57, but it will be understood that any conventional means may be employed to attach the power conductors, and a particularly suitable system is shown in said U.S. Patent No. 3,104,213. Similarly, the cover is suitably electrically insulated from the body of the cell since it is a conductor of electrolysis current. It is advantageously covered with heat insulation, as shown in the drawing.

As seen in FIG. 1, the liquid cathode, e.g. molten lead, and the electrolyte, e.g. molten alkali metal or alkaline earth metal salt, is introduced at the left-hand end of the cell body, the molten lead suitably being introduced through a conduit 80 and the electrolyte being introduced through a conduit 82. The conduit 82 extends upwardly into the electrolysis chamber 17 and discharges through a self-regulating float valve indicated diagrammatically at 84, of the type described in FIG. 5 of U.S. Patent No. 3,104,213. At the right-hand end of the cell body 10, there is provided at least one transverse wall extending between the side walls of the cell body and engaged by the cover 30 to define the downstream end of the electrolysis chamber proper and to define at least one end compartment. In the embodiment illustrated, there are shown two transverse walls 88 and 89 which define an end compartment 90 and an intermediate compartment 92, the intermediate compartment being provided with an outlet 94 for removal of dross which may accumulate upon the cathode and may be flushed out in the manner described in U.S. Patent No. 3,104,213. However, the second transverse wall 89 may be omitted along with the outlet 94. The cell bottom slopes downwardly in the vicinity of the transverse walls in order to form wells into which the transverse walls can extend to form liquid seals against passage of the lighter electrolyte into the end compartments as long as the liquid level of the cathode is maintained.

Since the principal desired product of the electrolysis reaction, i.e. the alkali metal or alkaline earth metal, is contained in the liquid cathode, means are provided for removing this fluid from the cell and, in accordance with this invention, means are provided to cooperate with the cell outlet structure to permit accurate adjustment of the level of the liquid cathode in the cell.

As seen more particularly in FIG. 2, the end compartment 90 is provided with an outlet defined by a cylindrical outlet conduit cylinder 102 which is rotatably mounted in a sleeve 104 rigidly secured in the cell bottom. The cylinder 102 defines a seat 105 for reception of the lower tapered end of a cylindrical sleeve 106. The outlet cylinder 102 is formed with a thread 107 which cooperates with a corresponding thread 108 in the sleeve 104 so that, upon rotation of the cylinder 102 within the sleeve 104, the cylinder will move axially in one direction or the other. The outlet cylinder 102 is hollow and discharges into an outlet conduit 109, a suitable fitting 115 being provided between the conduit 109 and the sleeve 104. In the drawing the outlet control mechanism de-

scribed above is exaggerated in size in order to facilitate the understanding of the invention. As seen in the drawing, portions of the above-described construction extend below the level of the support 14 and these portions may be disposed in a trough in the supporting surface or they may be formed so as to be accommodated within the support 14, which may have a greater height if desired.

Rotation of the outlet cylinder 102 to effect its axial displacement within the sleeve 104 is effected by any suitable means and, as shown in FIG. 2, an efficient rotating mechanism comprises a shaft 120 which extends downwardly through sleeve 106, and is connected at its lower end to the outlet cylinder 102 by means of cross bars 122. The upper end of the shaft 120 extends through the cover of the end compartment and a suitable shaft seal provided by seal members 124 and 125 is provided to seal the opening through the cover. The upper end of the shaft 120 is provided with a handle 127, suitably formed from electrically-insulating material, and a handle-securing bracket 128, provided with a set screw 130, is mounted adjacent the handle to facilitate the proper setting of the outlet cylinder 102. The set screw may be formed with a calibrated stem so that the exact position of the outlet cylinder can be determined.

The cylindrical sleeve 106 is formed with overflow apertures 132 and the level of the cathode in the cell is determined by the level of these apertures. Consequently, when it is desired to raise the level of the cathode, it is merely necessary to raise the sleeve 106 and, conversely, when it is desired to lower the level of the cathode, such can be effected by lowering the sleeve 106. It will be apparent that such raising and lowering of the sleeve 106 is effected by rotating outlet cylinder 102 which supports the sleeve 106 and controls its axial position. Consequently, when, in the course of operation of the cell, the anode-cathode gap increases due to wear of the anode faces, the gap can be returned to its desired optimum value by raising the level of the cathode a corresponding amount. This is readily effected merely by raising the outlet cylinder 102 by rotating it in the appropriate direction within the sleeve 104. The thread between the outlet cylinder 102 and the sleeve 104 has been exaggerated in the drawing to facilitate illustration and it can be of any desired form in order to make possible any desired increments of movement upon each adjustment of the cathode level relatively to the faces of the anodes. There may be a slight leakage of lead alloy between the threads but this will be a very minor amount compared with the total outflow of lead alloy from the cell and such leakage is taken into account in forming the outflow apertures 132 and in no way interferes with the operation or effectiveness of the cathode-level control system.

As previously indicated, one of the advantages of the construction of this invention is the fact that it is readily adapted for automatic control. Thus, since an increase in the anode-cathode gap causes a voltage increase, a relay can be readily connected to be actuated upon a voltage increase beyond a predetermined value and this relay can in turn be connected to a reversible motor having a shaft connected to the shaft 120 of the level control mechanism. Thus, when the voltage increase exceeds the predetermined value, the relay will be actuated to cause the motor to be energized and the cathode level will be raised until the voltage increase has been nullified, at which time the motor will be de-energized in response to the deactivation of the relay, and further adjustment will stop. This automatic regulating mechanism has not been illustrated but the manner in which it may be provided will be readily apparent to a person skilled in the art. Such a system is particularly effective in a cell operating for the electrolysis of molten salts and using a molten lead cathode as described.

There is thus provided an effective and accurate method and means for effecting regulation or adjustment of the anode-cathode gap in an electrolysis cell of the mobile

cathode type which in no way relies upon movement of the anodes. The significance of the need for adjustment of the anode-cathode gap is apparent from the following.

A mercury cell with new graphite anodes adjusted to a level that will provide a gap of $\frac{1}{4}$ " may, for example, indicate on the voltmeter that the operating voltage is 4.1. After the anodes wear away by $\frac{1}{16}$ ", the gap between the anodes and the surface of the flowing cathode will increase to $\frac{5}{16}$ " but then the voltage across the cell may jump to 4.2. Since it is not unusual for a mercury cell to have 30,000 amps applied to it, the energy loss due to the slightly increased gap will be

$$30,000 \times (4.2 - 4.1) = 3000 \text{ watts or 3 kw.}$$

These cells operate continuously 24 hours a day and that means a power loss of 72 kwh. per cell every day. A plant may have a hundred or more of such cells operating and the total power loss may become enormous. I have mentioned only a small increase in the gap between anode and cathode, but as the cell continues in service, the gap will become greater and greater. So will the power losses.

It is, therefore, not surprising that many patents have been issued for inventions relating to the adjustment of anodes. The idea underlying all prior patents is to lower the anodes relatively to the cathode. A legion of ingenious devices have been developed to effect this operation.

While the method and apparatus of this invention are particularly suitable for use in connection with the electrolysis of molten salts at high temperatures in the presence of a molten lead cathode, it will be understood that the invention is also fully applicable to mercury-cathode cells.

Mercury is expensive and minor increases in the thickness of the mercury film in a normal-sized cell will add several thousands of dollars worth of mercury to it. Further, mercury has poor wetting qualities and the viscosity of mercury changes drastically in relation to the content of sodium it absorbs. The situation is completely different when lead is used at the cathode. Its price is negligible by comparison and the wetting properties of lead are excellent and they are not affected even by relatively large quantities of absorbed sodium. However, mercury-cathode cells are becoming larger and larger. Cells operating on 120,000 amps have already been built. Current densities applied to mercury cells are also increasing. Devices for lowering the anodes have become very involved and costly and, since the anodes must be adjusted frequently, and in many cases individually, the labor involved is considerable. Mercury-cathode cell operation will, therefore, benefit from this invention.

A further feature of this invention is that it may be combined with other cell-regulating mechanisms such as those described in U.S. Patent No. 3,104,213. Normally the top of cylindrical sleeve 106 may be simply received in a recess in the lower face of cover 30, the recess being sufficiently deep to accommodate the desired vertical movements of the sleeve, and suitably insulated to prevent electrical contact between the cover and the sleeve. To provide for other adjustment mechanisms, however, the cover 30 is provided with a suitably large aperture 140 to permit sleeve 106 to pass through and a graphite cap 141 having a suitably tall cylindrical portion 142 with a bottom integral flange 143 is bolted or otherwise secured about the aperture 140.

The cap is provided with a top circular electromagnetic coil 145 and a bottom circular electromagnetic coil 146 suitably spaced from coil 145 in order not to interfere with it electromagnetically. The top of sleeve 106 is provided with a weighted plug 147 secured within the sleeve, as by welding. A circular collar 148, subject to magnetic attraction, is secured to the sleeve 106 at a point suitable for attraction by the electromagnet

145 when the latter is energized. A ring 149 is slidably disposed about sleeve 106 so that it rests on sleeve lugs 150. The lugs 150 keep ring 149 suitably above the surface of the end compartment.

5 The ring 149 is normally disposed below apertures 132 but may be raised to close apertures 132, as will be described. The ring 149 is secured to upright standards 151 and the tops of standards 151 are secured together by a metal ring 152 subject to magnetic attraction. The ring 152 is also of sufficient weight to keep lower ring 149 below the level of the liquid cathode.

In order to clean dross from the cell, the sleeve 106 is rapidly lifted by energizing the electromagnetic coil 145, which attracts sleeve ring 148, thereby lifting sleeve 106

15 and the slideable ring 149 disposed on the sleeve lugs 150. This lifting of the sleeve 106 interrupts the normal flow of liquid cathode through apertures 132 and instead permits a relatively more rapid flow of cathode lead into outlet cylinder 102. The cathode level drops in the

20 electrolysis chamber as well as in the chamber located between transverse walls 88 and 89 thereby permitting passage of the molten floating salt and the dross thereon under transverse wall 88. The molten salt with the dross thus pass into the chamber having the outlet 94.

25 Release of the energizing action, acting on the top electromagnetic coil, causes the weighted sleeve to fall and cover the outlet aperture. This causes the level of the dross and molten salt to rise in the chamber between the transverse walls and to pass out of the outlet 94.

30 When it is desirable to clean the bottom surface of the anodes, the cell current is turned off and the bottom electromagnet is energized. This causes the slide ring to rise and cover the sleeve apertures 132. The result is that the liquid level of the cathode rises to touch and

35 wash the undersurfaces of the anodes in the cell. In operation, the anodes become fouled due to sulfur dioxide formation thereon, encrustations due to foreign matter in the salt, etc. The flow of the cathode, particularly in the case of lead, against these gaseous inclusions and deleterious deposits cleans the anodes.

40 After the liquid cathode has cleaned the anode undersurfaces, the energizing action on the lower electromagnet is released and the ring falls downwardly to its normal position on lugs 150 of the sleeve, thereby uncovering sleeve apertures 132 to permit resumption of normal operation. The cell current is then turned on and the operation of the cell is resumed with the cleaned anodes. It will, of course, be appreciated that the anode cleaning mechanism above-described can be eliminated and that 50 the anodes can be similarly cleaned by raising the cathode level by rotating cylinder 102 to a sufficient extent.

45 It will be understood that various changes and modifications in addition to those indicated above may be made in the embodiments herein described and shown in the drawings without departing from the scope of the invention as defined in the appended claims. It is intended, therefore, that all matter contained in the foregoing description and in the drawings shall be interpreted as illustrative only and not as limitative of the invention.

55 60 I claim:

1. A horizontal electrolytic cell of the liquid cathode type having an electrolysis chamber including a bottom and at least one depending anode, said depending anode being fixedly supported and held in relation to said bottom, and wherein the cathode flows over said bottom and under said anode and underlies the electrolyte with the surface of said cathode being above the upper surface of said bottom, means for adjusting the anode-cathode gap in said chamber comprising a vertically adjustable means

65 70 for varying the level of said liquid cathode in relation to said anode, said adjustable means being effective to maintain the level of said liquid cathode above the level of said bottom in said electrolysis chamber and including a 75 perforated overflow sleeve member slidably mounted in

said chamber in sealing engagement with the bottom of said chamber, said sleeve member having an internal passage communicating with the exterior of said chamber, means threadably secured in said chamber for vertically adjusting said sleeve member with respect to said chamber and means for moving said sleeve member out of sealing engagement with the bottom of said chamber whereby liquid cathode can be conducted to the exterior of said chamber independently of the internal passage in said sleeve member.

2. A horizontal electrolytic cell of the liquid cathode type having an electrolysis chamber including a bottom and at least one depending anode, said depending anode being fixedly supported and held in relation to said bottom, and wherein the cathode flows over said bottom and under said anode and underlies the electrolyte with the surface of said cathode being above the upper surface of said bottom, means for adjusting the anode-cathode gap in said chamber comprising a vertically adjustable means for varying the level of said liquid cathode 20 in relation to said anode, said vertically adjustable means including a perforated overflow sleeve mounted within said chamber on a rotatable hollow cylinder means, said cylinder means being rotatably mounted in said bottom and vertically adjustable with respect to said chamber 25 upon rotation thereof.

10

5

3. A horizontal electrolytic cell as set forth in claim 2, wherein said cylinder means and said bottom are formed with cooperating thread means for vertically adjusting said cylinder means with respect to said bottom.

4. A horizontal electrolytic cell as set forth in claim 2 which further comprises a rotating mechanism connected to said rotatable cylinder for rotating said cylinder relative to said bottom, said mechanism extending vertically upwardly to the exterior of said cell.

5. A horizontal electrolytic cell as set forth in claim 2, wherein said chamber is provided with means for raising said perforated overflow sleeve independently of said rotatable cylinder means for draining the cathode directly through said rotatable cylinder means.

6. A horizontal electrolytic cell as set forth in claim 5 wherein said raising means comprises cooperating electro-magnetic means.
